UNITED STATES PATENT OFFICE.

WILLIAM H. DAY, OF EAST HAVEN, CONNECTICUT, ASSIGNOR, BY MESNE ASSIGNMENTS, TO REMINGTON RAND INC., OF NEW YORK, N. Y., A CORPORATION OF DELAWARE.

METHOD AND MEANS FOR MAKING INDEXES OR THE LIKE.

Application filed June 29, 1925. Serial No. 40,821.

This invention relates to indexes or files composed generally of individual card-like elements, and to the method and means of developing such an index from predetermined data, so that each element will have the data required to be imprinted or otherwise indicated thereon, disposed in substantially the same location upon the surface thereof.

More particularly, this invention relates to the method and means for making an index or file composed of a series of card-like members wherein the members are arranged in such a manner that a margin or other portion of each is exposed to view, whereby a user may readily observe the data imprinted or otherwise indicated upon said exposed margin or other card portion. The general practice in the past of making an index or file of this or similar type, has been to place the data upon the margin or other exposed portion of the card-like index element by means of a typewriter or in writing or in lettering by an individual, and because of the nature of these operations only one card or index element could be so provided with data at a time. Another method of preparing cards for such an index has recently been suggested, which is shown in Patent No. 1,530,107 issued to E. Coleman and dated March 17, 1925, wherein index elements of a card-like form are imprinted with the required data one at a time by means of the use of an attachment to an addressing machine.

Such methods are satisfactory where only a few cards are required at a time, or where perhaps one list of cards is required from a previously arranged list upon addressing machine type plates, or other transfer devices, but they are not economical where a number of duplicate lists or indexes are required, especially those wherein there are a comparatively large number of index elements of individual card-like form. This is especially true in cases of temporary lists of new subscribers and changes thereof, such as required in large telephone exchanges for the use of the information operators and others, or of a new installation of lists or indexes of subscribers or customers for such companies as telephone, telegraph, large department stores, credit bureaus, and the like. Such lists, especially the temporary ones and in indexes wherein many changes take place and which require a number of duplicate lists

of index elements, when made by the methods generally in use in the past, have been found to appreciably increase the cost of development of such indexes or the cost of the maintenance thereof. This cost has been largely due to the class of labor necessary to produce the lists, one card at a time, and to the possible errors, omissions, misfiling and losses occasioned by the necessary handling of large numbers of the index elements by various individuals.

It is desirable, therefore, in the development of an index or file, that the data be first arranged systematically and then be retained in such order until finally disposed in a proper receptacle or other holder, and that the various operations intermediate the first arrangement and the final disposition of the index elements be of an easily and readily understood nature so that even so-called unskilled labor may be employed to perform the same. For like reasons, the devices used for these intermediate operations should be readily manipulated, the movable parts of which are easily arranged and adjusted.

The principal object of this invention, therefore, is to provide an improved method for making indexes or files of the above noted types, by the use of which the cost of such indexes is appreciably decreased and errors, omissions, and misfilings are reduced to a minimum whereby the index or file finally obtained is of maximum value due to its accuracy and form and in the arrangement of the data thereon.

Another object of the invention is to provide means for making such an index or file by the method provided, said means being efficient in operation and readily manipulated.

Another object of this invention is to provide a device whereby an index or file may be made by the improved method and wherein cardlike elements in multiple may be imprinted with the required data while being in proper position for intermediate transfer to the holder or carrier of the index equipment without disarrangement of the order thereof.

Still another object of this invention is to provide such a device which is capable of duplicating predetermined data upon a number of sets or series of card-like elements arranged in multiple so that the data received

by each will be in relatively the same position thereon.

To these and other ends which will appear as the invention is subsequently described and claimed, my invention consists in the novel operations and combinations thereof and in the novel features and arrangements of parts and combinations thereof to be hereinafter described and claimed.

10 In the accompanying drawings:

Fig. 1 is a perspective view of a device embodying the features of this invention, and which is adapted for use in the making of indexes or the like by the improved method 15 of this invention;

Fig. 2 is a perspective view of the device shown in Fig. 1, showing the parts thereof in other positions;

Fig. 3 is a section on line 3—3 of Fig. 5, 20 showing a plan view of certain parts of the device shown in Fig. 1;

Fig. 4 is a bottom view of the parts shown in Fig. 3;

Fig. 5 is a section on line 5—5 of Fig. 3;

25 Fig. 6 is a section on line 6—6 of Fig. 3;

Fig. 7 is a detailed plan view of an index card blank carrier used with the device of this invention;

30 Fig. 8 is a side view of the carrier shown in Fig. 7;

Fig. 9 is a section on line 9—9 of Fig. 7;

Fig. 10 is a section on line 10—10 of Fig. 7;

35 Fig. 11 is a rear view of a series of index card blanks of one form or type adapted for use in the making of an index or the like;

Fig. 12 is a more or less diagrammatic side view of the index elements shown in Fig. 11;

Fig. 13 is a front view of a series of index card blanks of a somewhat modified form 40 or type, and

Fig. 14 is a rear view of a series of index card blanks of another somewhat modified form.

The type of index shown in the drawings 45 and hereinafter described, which the features of this invention are particularly adapted to make and for which the device shown is especially adaptable for performing one of the principal operations thereof, is of the overlapping form wherein the individual card-like elements are arranged substantially flatwise in a frame or holder, one upon the other, and wherein means of some form is provided whereby a margin of each of the elements 50 is exposed to view, although this latter feature is not necessarily required in all aspects of this invention. The means which provides that each element overlaps a predetermined amount so that a margin of each is exposed to view when a series of elements are arranged in position in an index or file, may be any one of the many well known forms.

For the purpose of illustrating my invention I have selected one type of card-like 55 index element as a preferred one by the use

of which an index or file may be made by the novel method and the novel features of this invention. In this instance, the selected card-like element is of the type whereby a series of them may be retained in overlapped relation with a margin of each exposed to view. A rear view of a series of these elements is illustrated in Fig. 11, in which the individual elements 10 are provided with struck-out tongues 11, the bases of which are spaced a predetermined amount from one margin 12 of the cord or element. Another card when nested between the tongues 11 and the body of the card and the marginal edge 13 thereof, is engaged by the base portions 14 of the tongue, will have its opposite margin 15 extended beyond the corresponding marginal edge of the first mentioned element, and therefore, exposed to view, as shown in Figs. 3 and 7. The tongues 11 of this particular form of index element 10 are also adapted to engage a supporting frame and retain the index element thereon by having the tongue portion 16 extend beyond the side edges 18 of the supporting strip 17, as indicated in dotted lines in Figs. 11 and 12. The patent to Irving Fisher, No. 1,048,956 dated December 24, 1912, shows and fully describes this type of index element.

Figs. 13 and 14 illustrate other series of other forms of overlapping elements wherein a margin is likewise exposed to view. In Fig. 13 the elements 19 are interlocked by means of the tongues 20 engaging the card next above within a slot or slit 21, and after a plurality of such cards are so interlocked the entire series may be suspended, if desired, from a suitable support such as a nail or the like, which is passed through the opening 22. For a more detailed description of this form of index element reference is made to the patent to Daniel A. Wilcox, No. 1,531,893, dated March 31, 1925. In Fig. 14, the elements 23 are provided with struck-out tongues 24, which in so far as the possibility of obtaining the required overlap is concerned, are analogous to the tongues 11 of the previously described element 10. The tongues 24 of the element 23, however, do not assist in retaining the elements upon a frame or holder. Such engagement is obtained by laterally extending a portion of each of the side edges or, as shown in Fig. 14, the entire side edge of the element, sufficiently to engage a frame member beneath opposing flanges 25 indicated in dotted lines on Fig. 14.

The device shown in the perspective views of Figs. 1 and 2, is in this instance, adapted to impress the required data upon the exposed margins of a plurality of any of the above or like types of card-like index elements substantially simultaneously, while at the same time retaining the elements in overlapped arrangement and in sequence. The particular means for impressing the

- data upon the index elements, in this instance, includes a stencil 26, but other means for obtaining impressions are possible, for instance, the use of type plates or of duplicating ink and, therefore, the mechanisms for using the selected transfer device may differ somewhat from the structure to be hereinafter described. The stencil 26 may be made from specially treated paper 27, if desired, which 5 is capable of receiving the printing characters 28 when the same are impressed therein by the type of an ordinary typewriter, which disrupts the material of the paper at the points of contact and adapts it to allow ink or other suitable fluid to flow therethrough. The specially treated paper, by this means, is converted into a stencil usually after having been mounted on a holder of cardboard or the like 29.
- 10 20 The device illustrated comprises a base or standard 30 having upwardly extended side members 31 and 32. Ink rolls 33, 34 and 35 are pivotally supported between the side members 31 and 32. Of these rolls 33 is the ink container and contacts with roll 34, which is one of the ink transferring rolls. The roll 34 contacts with the roll 35, which is another ink transferring roll. The diameters of these rollers vary so that continuous lines 15 or spots of ink will not be formed upon either roller, about its periphery. An inking roller 36 is provided which is pivotally connected to and supported by a swinging carrier, pivoted to the side members 31 and 32 at 37, and 25 30 which comprises the side arms 38 and 39, which are interconnected at the remote ends thereof by a handle 40. The roller 36 is also pivoted between the arms 41 of an operating holder having an operating handle 42 secured thereto. An engaging hook 43 is secured to the handle 42 and is adapted to hook under the handle 40 when the parts of the device are in the position shown in Fig. 1. The inking roller 36 is also provided with a rotating handle 44 by which the roller is rotated when in contact with the roller 35 and, in the position shown in Fig. 1, whereby ink is supplied to it from the ink roll 33 through the ink transferring rollers 34 and 35.
- 35 40 45 50 A transfer device of stencil plate holder 45 is provided. The holder 45 comprises an attaching portion 46 by which the holder is adjustably secured to the base 30 and a swingable portion 47, which is hinged at 48 to the portion 46. The attaching portion 46 of this holder is clamped between the pairs of blocks 49 and 50, and 51 and 52, by means of bolts 53. The blocks 50 and 52 loosely slide in longitudinally elongated openings 54 provided in the standard 30. Adjusting screws 55 and 56 are rotatably connected to the blocks 50 and 52, respectively, and extend outwardly therefrom through the wall 57 of the standard 30, being in threaded engagement therewith, whereby the rotation of these 55 60 65 screws will cause the blocks 50 and 52, together with the attached parts 46 and 47 to be moved relatively longitudinally in respect to the standard 30. Due to the loose sliding fit between the respective blocks 50 and 52 and 70 the openings 54, these screws may also cause lateral shifting of the holder portion 47 in respect to the standard 30 when either one of the screws 55 or 56 is rotated more or less than the other. For instance, if the screw 75 55 is not rotated and the screw 56 is rotated, the block 52 will be moved either forwardly or rearwardly, depending upon the direction of rotation, and if the block 52 is moved forwardly then the holder 45 will be shifted 80 laterally to assume a position shown slightly exaggerated in dotted lines in Fig. 3. The possibility, therefore, of both lateral and longitudinal shifting of the holder 45 allows the transfer device when mounted thereon to be 85 moved relatively to the index elements located beneath the same, so that the data thereon may be aligned with the marginal edges or other exposed portions of a series of index elements. After properly locating the transfer device holder by means of screws 55 and 56, the same may be located in position by means of the lock nuts 58. The transfer device or stencil plate 26 is detachably secured 90 to the holder 45, in any desirable manner, 95 such as by means of the straight pins 59 and the forwardly hooked pins 60, which engage the stencil plate 26 within suitable openings therein.
- 95 100 105 An opening 61 is provided in the portion 47 of the holder 45, and is located therein in proper position to be disposed below the transfer device, in this instance, the stencil portion 27. Beneath the opening 61 in the holder 45, and removably seated in a supporting portion 62 of the standard 30 is an index element carrier 63. The index element carrier 63 comprises a base block 64 to which is fastened an element engaging strip 65, an element supporting strip 66 and adjustable 110 side strips 67 and 68. The base block 64 is hollowed out as shown in Figs. 9 and 10, to form a base-plate 69, end walls 70 and 71 and side walls 72 and 73. The element engaging strip 65 is secured to the end wall 70 by any 115 desired means, such as screws 74, and the element supporting strip is secured to the end wall 71 by similar means, such as screws 75. The strip 65 extends above the baseplate 69 and is turned over and extends along the same to form a flange portion 76. The strip 66 extends above the plate 69 and is turned over and extends along the same, and gradually extends toward the surface thereof until 120 in contact therewith to form an inclined supporting portion 77.
- 120 125 130 The side strips 67 and 68 are retained against the side walls 72 and 73, respectively, by means of the headed screws 79. A reinforcing plate 78 is brazed or welded to each

of the side strips 67 and 68. The screws 79 pass through elongated openings 80 provided in the side strips 67 and 68, respectively, and in the reinforcing strip 78, and are then threaded into the side walls 72 and 73, respectively. The openings 80 are disposed in the side strips 67 and 68 in such a manner that the strips are allowed vertical movement relatively to the plate 69. Each of the side strips extends above and is turned over and extends along the plate 69 to form opposed flange portions 81 and 82, respectively. End portions 83 and 84 of the flange portions 81 and 82 are flared outwardly from the base block 64 to assist in guiding the edges of index elements being placed thereunder.

A rod 85 extends across the block 64 being supported by the side walls 72 and 73, in bearings 86. The rod 85 is provided with a handle 87 for rotating the same and at each end extends beyond the side walls. The extended ends of the rod 85 are reduced in diameter in such a manner that eccentric trunnions 88 are formed. The trunnions 88 pass through the side strips 67 and 68 and the plates 78 in elongated openings 89, which are disposed horizontally or parallel with the baseplate 69.

From the above description the following operation of the device will be apparent. A stencil or other data transferring device is provided upon which the required data has been arranged, which in this instance, consists of a series of names of individuals with their telephone numbers, in such a manner that each line of imprint will be uniformly spaced from another. The stencil 26 is placed upon the holder 45 by engagement with the pins 59 and 60. A series of blank index elements are arranged in overlapping relation whereby a marginal edge of one is exposed beyond another. This series of index element blanks is then slipped into a carrier, like 64, being located therein by engagement beneath the flange 76 of the strip 65, and suitably supported by the supporting portion 77 of the strip 66. The side flanges 81 and 82, respectively, overlying the side edges of the index elements are now depressed into clamping engagement with these edges of the index element by rotating the rod 85 so as to operate the eccentric ends 88 thereof in the openings 89 of the side strips 67 and 68 to draw the same downwardly toward the plate 69.

The carrier 63 with the series of index element blanks is then placed into the supporting seat 62 of the standard 30, where it is properly located by engagement with the sides of the opening 90 provided in the top plate 91 thereof. The stencil holder 45 is then disengaged from a catch member 92, which by means of a groove 93 springably engages the edge of the holder portion 45, and is swung downwardly upon the standard 30

above the series of index elements. The stencil 28 being, in this instance, made of specially prepared transparent paper allows the user to observe the marginal edges of the index element blanks therethrough and to ascertain if the characters upon the stencil are in proper alignment therewith to cause a properly arranged imprint thereon. In case the characters upon the stencil are not in proper alignment with the marginal edges, the adjustment above described regarding the stencil holder 45 is made, after which the inking roller is swung downwardly in its frame by means of the handle 40 and is rolled over the stencil 27 by means of the handle 44, the parts above described being in a position as shown in Fig. 2.

After the above operations have taken place the inking roller 36 is returned to the position shown in Fig. 1, the transfer device is removed from operative position by swinging up the holder portion 46, and the carrier 63 with the imprinted index elements is removed from the standard 30. A new transfer device or stencil may now be substituted or the same one may be used again, depending upon the requirements of the index being made. In case a duplicate index or a plurality of like indexes is required, it is desirable to continue the above operations upon other series of index element blanks clamped in similar carriers 63.

After being imprinted with the desired data the index elements are unclamped from the carrier 63 and slipped therefrom and then without disturbing the sequence of the series may be placed into the final filing frame suitable to retain the same. Due to the particular interesting feature of the form of index elements shown in Figs. 11 and 14, the series of elements is more readily arranged in overlapping relation and will also be more readily inserted into and slipped from the carrier 63 without disarrangement than elements not having this feature, care being required merely to insure that the same are not disarranged laterally while so doing. The form shown in Fig. 13, however, does not require even the care required regarding the lateral disarrangement, the elements being interlocked against both longitudinal and lateral movement relative to each other, while in the carrier 63 the flange 76 locates these forms longitudinally by engagement with the lowermost card and the side flanges 81 and 82 prevent lateral movement thereof in addition to the clamping feature thereof.

By the use of the stencil form of transfer device it is possible to typewrite the characters upon the stencil surface 27, from which a large number of series of index elements may be imprinted. The stencil may then be filed away for future use, or it may be changed by providing a new stencil surface thereto. The above method as described in reference to the

device shown, provides an easily operated and inexpensive method for making indexes or the like, the accuracy of arrangement and data being determined at the initial source, it 5 being duplicated more or less automatically thereafter.

While I have shown and described a preferred embodiment and a preferred method of performing the operations incident to the 10 making of an index or file, the invention is not limited to all of the details shown, nor to the operations or the order thereof described, as the same are capable of many modifications and variations without departing from the 15 spirit of the invention and the scope of the appended claims.

What I claim is:

1. The method of applying indicia to a series of equally spaced index strips, which 20 consists in rigidly supporting said series of strips, applying a semi-transparent stencil to the upper surface of said series of strips, said stencil having rows of printing previous to ink formed thereon, adjusting the position 25 of said stencil while observing said strips through said stencil until the rows of printing on the stencil coincide with said series of strips, passing an inking roller over said stencil, and removing the series of strips from 30 said support.

2. The method of applying indicia to a series of nested index cards having exposed edges forming a series of equally spaced strips, which consists in rigidly supporting 35 said cards in face to face position, applying a semi-transparent stencil to said series of strips, said stencil having rows of printing previous to ink formed thereon, adjusting the position of said stencil while observing 40 said strips through said stencil until the rows of printing on the stencil coincide with said series of strips, passing an inking roller over said stencil, and removing the series of strips from 45 said support.

3. Means for making indexes or the like, comprising a frame, an index element blank carrier removably mounted therein, having a plurality of overlapping index element 50 blanks thereon, a swingable transfer device holder adapted to be positioned over said blanks, means for adjusting said holder longitudinally and transversely of said blanks, a transfer device comprising a stencil having prearranged characters thereon removably 55 held thereby, and movable means to imprint the characters of said stencils upon said blanks.

4. In a stenciling device, a support adapted 60 to receive a series of nested index cards, clamping jaws along the edges of said index cards adapted to maintain the overlapping edges of said cards in a plane, a stencil having rows of printing thereon previous to ink, means for adjusting the position of said stencil and cards so that said rows of printing 65

coincide with the overlapping edges of the cards, and means for passing an inking roller over said stencil so as to print indicia along the overlapping edges of said series of cards.

5. In a stenciling device, a base member, 70 a stencil holder hingedly and slidably connected to said base member, means for securing a series of spaced strips to said base member below said stencil holder, means for adjusting the position of said holder transversely and longitudinally of said strips, and means for passing an inking roller over said stencil so as to imprint indicia from said stencil onto said strips.

6. Means for making indexes or the like, 80 comprising an index element blank carrier adapted to retain a plurality of overlapping index element blanks thereon, a transfer device comprising a stencil disposed over said blanks, means to align certain of the characters upon said transfer device with certain 85 corresponding portions of the blanks, and an inking roller adapted to cause the characters to be imprinted upon said blanks.

7. Means for making indexes or the like, 90 comprising an index element blank holder adapted to retain a plurality of index element blanks thereon, said blanks being adapted to internest and to overlap each other whereby a margin of each is exposed, a transfer 95 device having characters thereon arranged in lines one above the other, means to align each of the lines of characters with the exposed margin of each of the blanks, and means to imprint the characters so aligned 100 upon said margins.

8. Means for making indexes or the like, comprising an index element blank carrier adapted to retain a plurality of index element blanks thereon, said blanks being adapted to 105 overlap each other, whereby a margin of each is exposed, a transfer device comprising a stencil plate having margins thereon arranged in lines one above the other, means to align the lines of characters with the exposed 110 margins of said blanks, and an inking roller to imprint the characters so aligned upon said margins.

9. Means for making indexes or the like, comprising a frame, an index element blank 115 carrier removably mounted therein and adapted to retain a plurality of overlapping index element blanks thereon, a swingable transfer device holder adapted to be positioned over said blanks, a transfer device 120 having characters held thereby, and means to impress the characters thereof upon said blanks.

10. In a stenciling device, a support adapted to receive a series of overlapping index 125 cards, an inclined member associated with said support adapted to maintain the end cards of said series in a substantially horizontal plane, and means for stenciling indicia on the exposed edges of said overlapping cards. 130

11. In a stenciling device, a support adapted to receive a series of overlapping index cards, a retaining flange associated with said support and adapted to engage the end card 5 of said series to prevent the separation of said cards, and means for stenciling indicia on the exposed edges of said overlapping cards.
12. In a stenciling device, a support adapted to receive a series of overlapping index cards, a retaining flange associated with one end of said support and an inclined member with the other end thereof so as to support said cards in stenciling position, and means 15 for stenciling indicia on the exposed edges of said cards.
13. In a stenciling device, a support adapted to receive a series of index cards presenting successive, narrow, indicia-receiving faces, 20 said support having means to prevent shifting of said cards during a stenciling operation, a stencil movably supported above said cards and having rows of printing pervious to ink formed thereon, said rows registering 25 with said card faces, and inking means adapted to imprint said indicia on said card faces.
14. The method of applying indicia to a series of equally spaced index strips, which consists in applying a semi-transparent 30 stencil to the upper surface of said series of strips, said stencil having rows of printing pervious to ink formed therein, adjusting the position of said stencil relative to said strips both laterally and longitudinally until the 35 rows of printing register with said series of strips in a predetermined relation, and passing an inking means over said stencil, subsequently removing said inking means and stencil from said strips.
15. The method of applying indicia to a series of equally spaced index strips, which consists in applying a stencil to the upper surface of said series of strips, said stencil having rows of printing pervious to ink 40 formed thereon, adjusting the position of said stencil relative to said strips until the rows of printing are parallel to the edges and equally spaced from the ends of said series of strips, retaining said index strips and stencil 45 in adjusted position, and passing an inking means over said stencil, subsequently removing the inking means and stencil from the strips.
16. In a duplicating device, a support, 55 clamping means associated with said support for removably clamping a card to be imprinted, a transfer device having characters to be imprinted upon said card, means adjustably securing said transfer device to said support for adjustment to vary the position of the characters longitudinally and transversely relative to a card clamped on said support, and means to cause the imprint of the characters upon said card.
17. In a duplicating device, a support, 60 clamping means associated with said support for removably clamping an article to be imprinted, a transfer device, having characters to be imprinted upon said article, means adjustably mounting said transfer device on 70 said support for adjustment to vary the position of the characters longitudinally and transversely relative to an article clamped on said support, a swinging carrier on said support, and means to cause the characters to be 75 imprinted upon said article operably mounted on said carrier.
18. In a duplicating device, a support, means for securing an article to be imprinted on said support, a stencil having rows of 80 printing pervious to ink formed therein, said stencil having an adjustable mounting on said support for positioning over the article to be imprinted, a swinging carrier on said support, an inking roller movably mounted in 85 said carrier and operable in one position of the carrier to pass over said stencil, and inking means on said support for engagement with said inking roller in another position of said carrier to supply ink thereto.
19. In a duplicating device, a support, means for securing an article to be imprinted on said support, a stencil having rows of 90 printing pervious to ink formed therein, said stencil having an adjustable mounting on said support for positioning over the article to be imprinted, a swinging carrier on said support, an inking roller movably mounted in 95 said carrier, means for operating said roller, said carrier being adapted in one position to engage said inking roller for operation over said stencil, and inking means on said support for said roller.
20. In a duplicating device, a support, clamping means for detachably and rigidly 100 securing an article to be imprinted on said support, a stencil having rows of printing pervious to ink formed therein, a holder for detachably mounting said stencil, means mounting said holder on said support for adjustment laterally and longitudinally thereof, and inking means for movement over said 105 stencil to imprint said article.
21. In a duplicating device, a holder for a plurality of cards formed for interfitting 110 relation to provide substantially equal projecting margins, clamping means engaging and holding said cards in said interfitting relation and in alignment, a stencil having rows of printing pervious to ink, means adjustably mounting said stencil for adjustment 115 laterally and longitudinally of said support to position the rows of printing in alignment with the projecting margins of the cards, and means to cause the printing to be transferred 120 to said cards.
22. In a duplicating device, a support, means for securing an article to be imprinted on said support, a stencil having rows of 125 printing pervious to ink formed therein, 130

means mounting said stencil on said support for positioning over the article to be imprinted, a swinging carrier on said support, an inking roller mounted in said carrier and operable in one position of the carrier to pass over said stencil, inking means on said support for engagement with said inking roller in another position of said carrier, and means for holding said inking roller in engagement with said inking means in the last named position of the carrier.

23. In a duplicating device, a support, means for securing an article to be imprinted on said support, a stencil having rows of printing pervious to ink formed therein,

means mounting said stencil on said support for positioning over the article to be imprinted, a swinging carrier on said support, an inking roller mounted in said carrier and operable in one position of the carrier to pass over said stencil, inking means on said support for engagement with said inking roller in another position of said carrier, and a handle member carried by the inking roller formed for cooperation with the carrier to retain the inking roller in engagement with said inking means.

In witness whereof, I have hereunto set my hand this 24th day of June, 1925.

WILLIAM H. DAY.

CERTIFICATE OF CORRECTION

Patent No. 1,712,200.

Granted May 7, 1929, to

WILLIAM H. DAY.

It is hereby certified that error appears in the printed specification of the above numbered patent requiring correction as follows: Page 1, line 100, for the word "intermediate" read "immediate"; page 2, line 77, for the word "cord" read "card"; and that the said Letters Patent should be read with these corrections therein that the same may conform to the record of the case in the Patent Office.

Signed and sealed this 4th day of June, A. D. 1929.

(Seal)

**M. J. Moore,
Acting Commissioner of Patents.**

means mounting said stencil on said support for positioning over the article to be imprinted, a swinging carrier on said support, an inking roller mounted in said carrier and operable in one position of the carrier to pass over said stencil, inking means on said support for engagement with said inking roller in another position of said carrier, and means for holding said inking roller in engagement with said inking means in the last named position of the carrier.

23. In a duplicating device, a support, means for securing an article to be imprinted on said support, a stencil having rows of printing previous to ink formed therein,

means mounting said stencil on said support for positioning over the article to be imprinted, a swinging carrier on said support, an inking roller mounted in said carrier and operable in one position of the carrier to pass over said stencil, inking means on said support for engagement with said inking roller in another position of said carrier, and a handle member carried by the inking roller formed for cooperation with the carrier to retain the inking roller in engagement with said inking means.

In witness whereof, I have hereunto set my hand this 24th day of June, 1925.
